UNITED STATES PATENT OFFICE.

INGEMAR RYSTEDT, OF DAYTON, OHIO.

CLEANER FOR TOOTHED IMPLEMENTS.

1,170,345.

Specification of Letters Patent.

Patented Feb. 1, 1916.

Application filed January 15, 1915. Serial No. 2,457.

To all whom it may concern:

Be it known that I, INGEMAR RYSTEDT, a citizen of the United States, residing at Dayton, in the county of Montgomery and 5 State of Ohio, have invented new and useful Improvements in Cleaners for Toothed Implements, of which the following is a specification.

The present invention relates to a cleaning device for toothed implements.

In carrying out my invention it is my purpose to provide a cleaner for toothed implements, such as combs, rakes, forks or the like which will act upon both the sides 15 and ends of the teeth to remove all foreign matter therefrom.

It is also my purpose to provide a device of this character which may be readily applied to toothed implements of the ordinary 20 construction and which shall embody the desirable features of simplicity in construction, cheapness in manufacture and thoroughly efficient for the purpose desired.

In the drawings: Figure 1 is a perspective view of a comb provided with my improvement, Fig. 2 is a similar view illustrating the arrangement of parts when the teeth of the comb are operated upon by the 25 device for cleaning the same, Fig. 3 is a horizontal sectional view approximately on the line 3—3 of Fig. 1, the same being greatly enlarged, Fig. 4 is a similar view approximately on the line 4—4 of Fig. 1, Fig. 5 is a detail sectional view approximately on the line 5—5 of Fig. 2, Fig. 6 is a perspective view of one of the toothed 30 scraping members.

Referring now to the drawings in detail, in which similar characters indicate like 40 parts throughout, the numeral 1 designates an ordinary hair comb. The end teeth 2 and 3 are of a greater width than the intermediate teeth and the said end tooth 2 is provided upon its outer edge with a notch 4. The opposite sides of what may be 45 termed the body of the comb are preferably centrally formed with a longitudinally extending depression providing a finger hole 5.

The improved cleaner includes a pair of 50 plates 6 and 7, said plates being arranged upon opposite sides of the comb 1. If desired, the plates may be connected at one of their ends, thus providing a substantially U-shaped element, but the said plates 55 terminate a slight but suitable distance inward of the end of the comb provided with

the widened tooth 2, while the opposite ends of the plates are connected through the medium of a removable element, preferably in the nature of a screw 8, the said screw 60 passing through an elongated slot or opening 9 in the tooth 3. The inclination of this slot or opening 9 corresponds with the inclined edges 10 of the series of teeth of the comb. 65

Hingedly secured, as at 11, to the connected ends of the plates 6 and 7, is a cap or closure 12, the same comprising a cross sectionally U-shaped or channel member and has its free end provided with an angularly extending portion 13, the outer wall of which terminates in a spring tooth 14, and the said tooth is adapted to engage with the notch 4 in the tooth 2 when the said cap is swung over what may be termed 70 the outer edge of the body of the comb and the inner edges of the angular extension 13 contacts with the ends of the plates 6 and 7 when the cap is in its closed position.

The end tooth 2 is provided with a slot 80 15, the same being arranged at an angle or curved to correspond with the angular or curved edges 16 of the series of teeth of the comb located away from the said slot.

The plates 6 and 7 may be provided with 85 depressions forming finger holds 17 and are provided with inwardly projecting studs or rivets 18 which are received within longitudinally arranged slots 19 provided in the side members 20 and 21 of the cleaning or 90 scraping elements for the inner edges 10 and 16 of the series of teeth. The members 20 and 21 have their edges provided with a plurality of laterally disposed scraping members 22 and 23 respectively, the scraping 95 members 22 engaging with the edges 16 of the teeth of the comb, while the cutting members 23 engage with the edges 10 of said teeth. The cutting members 22 and 23 are preferably in the nature of flat resilient 100 elements having chisel-shaped engaging edges, and the same may be connected with the members 20 and 21 in any desired or preferred manner or the said cutting members may be formed integral with the said 105 members, if desired. The ends of the plate 20 and 21 may be, and preferably are, angular so as to contact with the outer edges of the end teeth 2 and 3, the pivot 8 securing one of the said plates to one of the outer 110 plates 6 or 7, while a second pivot member 24 passes through the inclined slot 15 of the

22
tooth 2 and serves for sustaining the said plate upon the comb. In this connection, however, it should be stated that the members 18 are in the nature of headed elements, so that the members 20 and 21 are slidably but securely connected with the plates 6 and 7.

The outer edges of the teeth 2 and 3 are beveled or curved to correspond with the bevel or curvature of the edges 10 and 16 of the inner series of teeth. The plates 20 and 21 are permitted a limited sliding movement in a longitudinal direction on the comb and when the cleaner is operated the scraping members 22 and 23 will be also moved longitudinally to contact with the edges 10 and 16 of the inner series of teeth as well as with the inner edges of the end teeth 2 and 3, while the side plates will engage with the opposite sides of the comb so that foreign matter between the teeth or against the sides of the teeth will be removed. It is, of course, to be understood that the member 12 is swung to the position illustrated in Fig. 2 before the device can be operated. It is to be further noted that the slots or openings 9 and 15 respectively, engaged by the members 8 and 24 respectively, serve as stops to limit the outward movement of the cleaning device.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what I claim is:

40 1. In combination, a toothed member having tapered teeth, the two end teeth thereof each being enlarged and provided with a curved slot, each slot being curved similar to the curve of the side of the several teeth of the comb located away from said slot, and a cleaner member movable longitudinally of the comb teeth comprising two cleaning elements, a pivot member for each of the cleaning members arranged one in the curved slot of each of the end teeth and the said cleaner members adapted to be moved longitudinally of said comb teeth by virtue of such pivot engagement with the slots of the

end teeth, whereby the cleaning elements may be guided along and to contact closely 55 the whole length of the comb teeth.

2. The combination with a toothed member having tapering teeth, the two end teeth thereof each being enlarged and provided with a curved slot, each slot being curved 60 similar to the curve of the sides of the several teeth of the comb located away from said slot, and a cleaner member movable longitudinally of the comb teeth comprising each two spaced plates arranged upon the 65 opposite faces of the comb, the plates of one of the members disposed in contact with the outer sides of the plates of the other member, pivots compressing the side members of the cleaners passing through the curved slots 70 in the end teeth, cleaners including elements arranged between the teeth of the comb and in contact therewith and adapted by virtue of the pivots arranged in the slots of the end teeth to be guided along and to contact 75 closely the whole length of the tapered teeth.

3. In combination with a toothed member having tapering teeth, the end teeth being widened and provided with slots which are curved similar to the curve of the side of the 80 several teeth of the comb located away from said slot, a cleaner member comprising two longitudinally movable elements arranged upon the opposite sides of the comb, a binding element for the sides of the cleaner members comprising a guide pin arranged in the curved slots of the end teeth, whereby the cleaner members by virtue of the said engagement contact with the teeth throughout the entire length of said teeth, transverse 85 elements carried by the said cleaner members engaging with the opposite edges of the teeth of the comb, one of the widened end teeth having a notch, a cap connected with one of the elements of the cleaner member, a 90 spring tooth for the cap, and said tooth adapted to engage in the notch of the mentioned end tooth to lock the cleaner on the comb.

In testimony whereof I affix my signature 100 in presence of two witnesses.

INGEMAR RYSTEDT.
